UNITED STATES PATENT OFFICE.

SAMUEL C. ROBISON, OF LEXINGTON, KENTUCKY, ASSIGNOR OF NINE-TWENTIETHS TO THOMAS G. WIGGLESWORTH AND ONE-TENTH TO WILLIAM G. WIGGLESWORTH, OF LEXINGTON, KENTUCKY.

HEMP-BRAKE.

No. 839,208.

Specification of Letters Patent.

Patented Dec. 25, 1906.

Application filed April 9, 1906. Serial No. 310,744.

To all whom it may concern:

Be it known that I, SAMUEL C. ROBISON, of Lexington, in the county of Fayette and State of Kentucky, have invented certain new and useful Improvements in Hemp-Brakes; and I hereby declare that the following is a full, clear, and exact description thereof, reference being had to the accompanying drawings, which form part of this specification.

This invention is an improved machine for breaking and cleaning fibrous plants, such as hemp, sisal flax, &c.; and its object is to mechanically separate the fibers from the woody matters or shreds in a thorough manner and at the same time keep the fibers in good condition and free or practically free from snarls and tangles, which would render them useless for subsequent manufacture into rope, bagging, &c., for which they are customarily employed.

To these ends the invention is designed to keep the fibers continually moving endwise through the machine and to subject them to such repeated workings that they will be freed from the woody useless and injurious portions of the plant and will be rendered flexible and pliable and clean; and the invention consists in the novel construction and combinations of mechanisms for accomplishing the desired objects, as hereinafter described and claimed, and in the accompanying drawings I have illustrated a machine which embodies the invention in the best form now known to me; but as it is capable of modification within the scope of the invention I do not restrict myself to the particular form and arrangement of parts shown in the drawings.

In said drawings, Figure 1 is a side elevation of the complete machine. Fig. 2 is a side elevation of the opposite side of the machine. Fig. 3 is a detail plan view of the driving mechanism shown in Fig. 2. Fig. 4 is an enlarged longitudinal section through the main portions of the machine.

In the drawings, 1^a 1^b designate breaking-rolls, preferably longitudinally corrugated or ribbed, as shown, and journaled in suitable bearings on the main frame of the machine, said rolls being arranged transversely of said machine. These rolls are intergeared and driven in opposite directions by a train of gears 1^b 1^a 1^d 1^c, gear 1^c being fast on

the shafts of the rolls and gears 1^c 1^d being journaled on studs fixed to the main frame. 55 One of said rolls, preferably the upper, may be journaled in yielding bearings pressed toward the other roller by stout springs 1^f, adjustable by bolts and nuts 1^g, as indicated in the drawings. The rolls can be driven at 60 suitable speed by means of a large gear 1^h on the shaft of roll 1, meshing with a pinion 3^a on the main shaft 3, which is journaled in suitable bearings on the frame, located at the inner side of rolls 1 1^a.

After passing the breaking-rolls 1 1^a the broken stalks are fed between crushing-rolls 2 2^a, journaled in suitable bearings on the main frame at the inner side of the breaking-rolls, the upper one of the crushing-rolls being preferably journaled in yieldable bearings and forced toward the other roll by means of springs 2^b, adjustable by nuts and bolts 2^d, as shown. The crushing-rolls may be driven at proper speed in opposite directions by 75 means of a train of gears 2^e 2^f 2^g 2^h, the gears 2^e 2^h being fast on the shafts of rolls 2 2^a and the intermediates 2^f 2^g being journaled on studs attached to the main frame. Gear 2^f also meshes with gear 1^b on roll 1 and is 80 driven from and by the latter. After passing crushing-rolls 2 2^a, by which the shreds previously broken by the breaking-rolls are crushed and disengaged from the fibers, the fibers and stalks pass over a breaker-bar 3^b, 85 on which they are broken by the action of ribs 3^c on a beater-cylinder 3^d, which is mounted upon and rotated with the main shaft 3 and rotates in a direction toward the break-bar, so as to beat down the fibers passing thereover. This beater separates a large portion of the shreds from the fibers, and its action is supplemented by a secondary beater 3^e, located below the breaker-bar and mounted on a shaft 3^f, which is rotated in a direction 90 contrary to shaft 3 by suitable gearing or, as shown, by means of a belt 3^g, running over a pulley 3^h on shaft 3 and under a pulley 3ⁱ on shaft 3^f to a fan-pulley hereinafter referred to.

The beaters 3^d 3^e are preferably provided 100 on their peripheries with longitudinal bars 3^c, triangular in cross-section and adapted to strike the fibrous stalks rapidly and alternately after they leave the breaker-bar and knock the shreds out of the fibers, comb the 105 fibers out straight, and work them into a pli-

able condition. After passing the beaters the fibers are directed into a rubbing and separating apparatus by means of an air-blast hereinafter described. This apparatus comprises a large cylinder 4, provided with longitudinally-disposed bars 4^a, approximately triangular in cross-section, a coacting endless rubber or cleaner 5, having a series of transversely - arranged triangular bars 5^a, adapted to coact with bars 4^a on cylinder 4, and an endless fiber-carrier 6, running around cylinder 4 and between it and the rubbing device 5 and adapted to remove the cleaned fibers from the cylinder 4 in a smooth and orderly condition.

The cylinder 4 is mounted on a shaft 4^b, journaled in suitable bearings on the main frame and driven by suitable means in a direction opposite to the rotation of beater 3^a. As shown, shaft 4^b carries a sprocket 4^c, driven by a sprocket-chain 4^d from a sprocket 1^m on the shaft of roll 1.

The endless cleaner or rubber 5 runs over pulleys 5^d 5^e, mounted on transverse shafts 5^b 5^c, journaled on the main frame adjacent cylinder 4, so that the bars 5^a on the lower run of the endless rubber will alternate with and engage between the bars 4^a on cylinder 4, by which motion will be imparted to the endless cleaner, and the fibers caught between the bars 4^a and 5^a will be rubbed and worked up by the rubbing and rocking action of the bars 5^a against and between the bars 4^a.

The fiber-carrier 6 comprises endless side chains running over cylinder 4 and pulleys 6^b on a shaft 6^c, journaled in the mainframe in rear of cylinder 4, the side chains being connected by rods 6^d at regular intervals, which rods are adapted to engage the bottoms of the recesses between adjacent bars 4^a on cylinder 4, which thus forms a kind of driving-sprocket for carrier 6, and the fibers passing between the bars 4^a 5^a pass over rods 6^d and will be removed from the cylinder 4 by the upper run of carrier 6, as is obvious, and taken thereby to and over the pulleys 6^b, where they are discharged onto a final beater 7, over which they pass to delivery-carriers 8 and 9, as shown.

The beater 7 is preferably a cylinder provided with longitudinal bars 7^a, preferably triangular in cross-section, and is mounted on a shaft 7^b, which is driven by a crossed belt 7^c from a pulley 3^m on shaft 3. The delivery-carriers 8 and 9 preferably are constructed substantially like carrier 6—that is, of side chains connected by rods 8^a 9^a. The carrier 8 runs over sprockets 8^c 8^d, mounted on shafts arranged transversely of the main frame, as shown. The carrier 9 runs over sprockets 9^b 9^c 9^d, mounted on shafts suitably supported on the main frame, carrier 9 having a triangular run, a short downwardly-inclined portion between sprockets 9^c 9^b,

which is adapted to direct the fiber discharged by carrier 6 onto the beater 7, and an upwardly-inclined run between sprockets 9^b 9^d, parallel with the upper run of carrier 8, so that the fibers will be carried away from beater 7 between the parallel runs of carriers 8 and 9. The carriers 8 and 9 can be driven by a belt 4^m, running over a pulley 4ⁿ on shaft 4^b, the said belt running under a pulley 9^m on the shaft carrying sprockets 9^b to and over a pulley 8^m on the shaft carrying sprockets 8^d and back to pulley 4ⁿ, as shown. In this manner both sets of carriers 8 and 9 are moved in the right direction.

In order to direct the fibers across the space between the beater 3^a and the rubbing and cleaning devices, I preferably employ an air-blast, which is derived from a fan located in a casing 10 beneath the main frame and having a pulley 10^a on its fan-shaft, which is driven by belt 3^m from the pulley 3^b, the return run of the belt passing under an idler 3^d as shown. The air is conducted from the fan-casing through a trunk 10^b to a head 10^c, located below and adjacent to the first beater 9^a in such position as to drive the loose partly-cleaned fibers upward to and between the meeting-points of the cleaner-belt 5 and cleaning-cylinder 4. The shreds separated from the fibers by the beaters 3^a 3^b can be dropped into a box or receptacle 10^d, which is connected by a trunk 10ⁱ with the casing of fan 13, and the shreds can be blown from receptacle 10^d through trunk 10ⁱ to fan 13 by means of air-jets supplied from the pips 10^b 100 through pipes 10^j, or other suitable manner. Any other suitable means for removing the shreds can be employed.

The fan 13 may be one of the ordinary pneumatic blower-fans such as used in pneumatic stackers and is adapted to discharge the shreds and matters separated from the fibers and dropped into its casing through a pipe 13^k, which can be extended to any suitable discharging-point. The fan 13 can be operated in any desired manner, and it is indicated in Fig. 1 as operated by means of belt 13^b and pulley 13^a from a pulley on the shaft 7^b.

The endless-belt rubbing device 5 can have its tension adjusted by mounting one of its supporting-shafts 5^b in adjustable bearings which are held outward so as to tension the belt by means of springs 12 on rods 12^a, attached to the bearings, and whose tension is regulable by nuts 12^b.

The stalks are fed into the machine between the breaking-rolls 1 1^a from a platform 11, mounted on the machine at a convenient point in advance of said breaking-rolls.

Operation: The stalks of fibrous material are fed in endwise between rolls 1 and 1^a, by which they are broken or cracked into short lengths. Then the cracked stalks pass between the crushing-rolls 2 2^a which crush

the woody matters in the broken stalks and loosen them from the fibers. The stalks then pass on over breaker-bar 3^b and are struck by the bars 3^c on the first beater 3^d, the tendency of which is to drive the stalks down and to knock the shreds out of the fibers. The descending fibers are struck upwardly by the bars on the oppositely-rotating beater 3^e and pushed outward over the jet-head 10^c, by which they are blown upward against the beater 3^a again, so that the fibers are further beaten and combed by bars 3^c, and by the combined action of the said beater and air-blast the fibers are directed to and between the endless rubbing device 5 and the separating-drum 4, and the fibers are caught and held between the bars 4^a and 5^a, and as these bars travel together the rubbing and scrubbing action on the fibers tends to thoroughly separate them from any woody matters still adhering thereto. After passing through the rubbing devices the fibers are carried over by the endless carrier 6 to the delivery-carriers 8 and 9; but before reaching the latter they are whipped out by the final beater 7, which produces the final separation of the fibers from the shreds and small woody matters, and the clean fibers are delivered by the chains 8 and 9.

30 The main frame may be mounted on wheels, if desired, so as to be transportable from place to place, axle-bolsters being indicated at 16 16 in Fig. 1.

Having described my invention, what I claim as new, and desire to secure by Letters Patent, is—

1. In combination, breaking-rolls, crushing-rolls, a beater, a cleaning apparatus adapted to successively operate upon the stalks and fibers, and an air-blast to carry the fibers from the beater to the cleaning devices, substantially as described.

2. The combination of breaking-rolls, crushing-rolls operating upon the broken stalks; a beater operating upon the crushed and broken stalks; apparatus for rubbing the fibers, and means for cleaning the rubbed fibers; with an air-blast to direct the fibers from the beater into the rubbing devices, substantially as described.

3. The combination of means for breaking stalks, means for crushing the broken stalks, a rotary beater, a second oppositely-rotating beater; rotary rubbing devices for the beaten fibers, and means for cleaning the fibers, substantially as described.

4. The combination of corrugated rolls for breaking the stalks; rolls for crushing the broken stalks; a beater for separating the shreds from the stalks, and a second beater coacting with the first beater; with a rotary ribbed cylinder, an endless rubbing device coacting with said cylinder, means for removing the fibers from said cylinder, and an air-blast for directing the fibers from the beaters

to said rubbing-cylinder, substantially as described.

5. In a machine for breaking and cleaning hemp, &c., the combination of means for breaking the stalks, means for crushing the broken stalks; and a beater for separating the shreds from the stalks; with a rotary ribbed cylinder, and an endless rubbing device coacting with said cylinder; with a third beater operating upon the fibers after leaving the rubbing-cylinder, and endless carriers for delivering the cleaned fibers.

6. In a machine for breaking and cleaning hemp, &c., the combination of means for breaking the stalks, means for crushing the broken stalks, and upper and lower beaters, between which the crushed stalks are beaten, means for rubbing the beaten fibers; with a third beater operating upon the fibers after leaving the rubbing devices, and means for delivering the cleaned fibers.

7. In a machine for breaking and cleaning hemp, &c., the combination of means for breaking the stalks, means for crushing the broken stalks; beaters for separating the shreds from the stalks, a rotary ribbed cylinder and an endless series of bars coacting therewith to rub the fibers, means for removing the fibers from said cylinder, and means for cleaning the fibers delivered from said cylinder, substantially as described.

8. The combination of corrugated rolls for breaking the stalks, rolls for crushing the broken stalks, beaters for separating the shreds from the stalks, a rotary ribbed cylinder and an endless series of bars coacting therewith to rub the fibers, means for removing the fibers from said cylinder, an air-blast for directing the fibers from the beaters to said rubbing-cylinder, and means for cleaning the fibers delivered from said cylinder, substantially as described.

9. In a machine for treating fibrous plants, the combination of a ribbed cylinder, with an endless rubbing device adjacent said cylinder and provided with ribs adapted to engage and coact with those on the cylinder to rub the fibers; with an endless carrier running around the cylinder and between it and said endless rubbing device to remove the fibers after treatment, substantially as described.

10. The combination of means for breaking and crushing stalks, beaters for removing the shreds from the stalks, and a fiber rubbing and cleaning device, comprising a ribbed cylinder, and an endless series of bars or ribs coacting with the ribs on the cylinder; and an endless carrier running around the cylinder to remove the fibers after treatment, substantially as described.

11. The combination of means for breaking and crushing stalks, and beaters for removing the shreds from the stalks; of a fiber rubbing and cleaning device, comprising a ribbed cylinder, and an endless series of bars

- or ribs coacting with the ribs on the cylinder; with means for directing fibers from the beaters to the cylinder, and means for removing the rubbed fibers from the cylinder.
12. The combination of rolls for breaking the stalks; rolls for crushing the broken stalks, a breaker-bar adjacent the crushing-rolls, a rotary beater coacting with the breaker-bar, a rotary ribbed cylinder adjacent the beaters, an endless series of bars coacting with said ribbed cylinder, means for directing the fibers from the beaters to said cylinder, an endless stripping device running between the cylinder and coacting series of bars; and a second beater, for finally cleaning the fibers, substantially as described.
13. The combination of rolls for breaking the stalks; rolls for crushing the broken stalks, a breaker-bar adjacent the crushing-rolls, a rotary beater coacting with the breaker-bar, a second rotary beater coacting with the first beater, a rotary ribbed cylinder adjacent the beaters, an endless series of bars coacting with said ribbed cylinder, means for creating an air-blast to direct the fibers from the beaters to said cylinder, an endless stripping device running between the cylinder and coacting series of bars, a third beater, an air-blast adjacent the third beater, 30 and endless delivery-carriers, substantially as described.
14. In a machine for breaking and cleaning fibrous plants, the combination of corrugated breaking-rolls, crushing-rolls operating upon the broken stalks; oppositely-rotating beaters operating upon the crushed and
- broken stalks; means for rubbing the fibers after they have passed the beaters, and means for cleaning the rubbed fibers.
15. In a machine for breaking and cleaning hemp, &c., the combination of means for breaking the stalks, means for crushing the broken stalks; oppositely-rotating beaters between which the crushed stalks are beaten; means for rubbing and cleaning the beaten fibers, and a terminal beater, substantially as described.
16. In a machine for breaking and cleaning hemp, &c., the combination of means for breaking the stalks, means for crushing the broken stalks, a breaker-bar over which the crushed stalks are passed; oppositely-rotating beaters, rubbing devices for the beaten fibers, and means for removing the fibers from the rubbing devices, substantially as described.
17. In a machine for breaking and cleaning hemp, &c., the combination of means for breaking and crushing the stalks; oppositely-rotating beaters for separating the shreds from the stalks; a rotary ribbed cylinder, an endless device coacting with said cylinder to rub the fibers, and means for directing the fibers from the beaters into the rubbing devices.

In testimony that I claim the foregoing as my own I affix my signature in presence of two witnesses.

SAMUEL C. ROBISON.

In presence of—

W. E. CASSIDY,
J. B. FAULKNER.
